UNITED STATES PATENT OFFICE.

JAMES G. WILSON, OF LARCHMONT, NEW YORK.

BAFFLE FOR FIREPROOF SHUTTERS.

957,923.

Specification of Letters Patent. Patented May 17, 1910.

Application filed January 9, 1909. Serial No. 471,391.

To all whom it may concern:

Be it known that I, JAMES G. WILSON, a subject of the King of Great Britain, residing at Larchmont, Westchester county, State 5 of New York, have invented a new and useful Improvement in Baffles for Fireproof Shutters, of which the following is a specification.

My invention relates to sliding or rolling 10 shutters made of fire proof material and is particularly applicable to the well known type of such shutter constituted of interlocking metallic slats.

The object of my invention is to provide 15 a means by which, when the shutter is closed, any transit of hot air, gas, noxious vapors and flames is prevented from taking place across or around the interior end or edge of the shutter.

20 By the interior edge or end I mean, in the case of a rolling shutter, that edge or end which is adjacent to the barrel or shaft upon which the shutter rolls. In the case of a straight sliding shutter, I mean that 25 edge or end which is most remote from the opening to be protected when the shutter is fully open. But in the case of such straight sliding shutters, my invention may be applied to each and every edge of the 30 shutter when said shutter is closing its opening.

My invention is more particularly intended for shutters of the rolling type as above mentioned and may be used in such 35 type of shutters, not only to prevent the passage of gases, vapors, flames, etc., as aforesaid, from one side of the shutter to the other, but also to completely cut off such gases, vapors, flames, etc., from access to 40 the shutter coil and the casing surrounding the same, thereby in many, if not in most instances avoiding injury to the mechanism proper of the shutter so that the same will, except in the case of the most severe con- 45 flagrations, be uninjured by fire and capable of being re-used with but slight repair and adjustment.

50 My improved device may, as will be seen, be arranged to operate automatically either by means fusible at a given temperature, or mechanically. If preferred, I may arrange one form of my improved device to operate by hand.

55 Referring to the drawings, Figure 1 illustrates in perspective a preferred embodiment of my invention as applied to a rolling slat

shutter, the left hand side of the shutter being cut away and shown in section. Fig. 2 is a vertical section along the same line as the sectioned perspective of Fig. 1, the 60 upper portion only of the shutter being considered. Fig. 3 illustrates a modification of my invention in which the device is applied to the shutter instead of to the coil casing as in Figs. 1 and 2. Fig. 4 is like Fig. 3 65 but shows a different form of my invention as applied to the shutter proper. Fig. 5 is an enlarged detail of an end of my invention as shown in Fig. 4, Fig. 6 is an elevation, part broken away, showing my invention as 70 applied to a straight sliding shutter; Fig. 7 is a section along the line 7—7 of Fig. 6; Fig. 8 is a detail showing one mode of actuating my device; and Fig. 9 is a detail showing a modified mode of operating my 75 invention.

Referring to the drawings, A is a rolling metallic shutter composed of interlocked slats a, and arranged to protect a door opening B. This shutter is attached to and coils 80 upon a center roller C in a manner generally well known in the art, the chain D co-operating with a suitable sprocket wheel E (indicated only) so geared to the shutter coil as to roll and unroll the same and leave 85 it in any desired position as to the more or less complete closure of the shutter. A casing F of fire proof material is affixed to the wall G above the shutter opening and surrounds the shutter coil as shown, the wall G 90 itself closing the casing on its open side.

The shutter being closed there is, in the constructions usually employed, a space necessarily existing between the lower edge of the casing F and the shutter on one side 95 and the lower edge of the lintel H and the shutter on the other side. In the case of severe fire, drafts are apt to be established by which the flame is sucked up through these spaces into the casing on the one side 100 or the other according to the side upon which the fire starts, which flame may pass clear around the shutter coil and issue therefrom on the other side thus becoming a means of communicating fire from one side 105 of the protective shutter to the other; even should the fire not be so severe as to pass flames from one side of the shutter to the other, there will still be danger of smoke and noxious fumes being so transferred and becoming a source of damage through tainting 110 of the goods or the room which the

shutter is designed to protect. The shutter coil C, whether a simple tubular shaft, a tube or equivalent series of barrels connected by springs to a central shaft, or made in some other preferred fashion is also liable to be severely damaged and rendered worthless for any future purposes if flame or hot air gains access to the casing.

My invention provides against any and all of the above risks.

It consists of two iron slats I and I' of L shaped section and extending the whole width of the shutter, the one slat being hinged to an angle iron e fixed to the building structure in any usual way and to which the lower edge of casing F is also attached and the other being similarly hinged to the bottom of the lintel on the other side of the shutter; at the end of each of these angled slats is an extension or lever arm J in the plane of the wider element of the L and perpendicular to the line of hinges, said arm terminating in an enlarged portion J'. Originally these angled slats are in the position shown in Fig. 2, the arms J being drawn up to the lintel and casing respectively and joined to eyes K by fusible links L, these links being made to melt at a predetermined temperature. Upon the melting of the links and by reason of the excess weight of the wider element b of the baffle plates and the weights J' at the ends of the levers, the baffle plates will turn upon their hinges so as to throw up the narrower element c of said baffle plates against the shutter slat on each side, thereby completely closing the spaces between the lower edge of the casing and the shutter on one side and the lintel and the shutter on the other side and blocking off from the casing F with its interior mechanism all access of smoke, hot air, vapors or flames. To reset the baffle plates requires merely that the weighted arms J be raised into the position of Fig. 2, and new fusible links L inserted to retain said arms in the position shown. Ordinarily the baffle plates are set and in no way interfere with the normal position of the shutter, becoming operative, and dropping into closed position only when the temperature rises to whatever limit may have been determined upon as dangerous.

Fig. 3 shows a modification of my invention in which the baffle plates are attached to the shutter proper instead of to the casing and lintel adjacent to the shutter. These plates d, d, in the modification shown, are of fireproof material such as sheet iron and may be resilient. The plates are preferably rectangular in form, but may be angular and they extend clear across the width of the shutter, and are riveted or otherwise suitably attached to the two sides of shutter slats as shown in the figure. When the shutter is coiled these flaps are forced down on

each side against the slats by the weight of the superimposed shutter layers, or fit as to the inner flap in a recess M provided in the roller, as the shutter rolls upon the coil and do not add to the diameter of said coil. 70 When the shutter is lowered, these plates are freed as the slat which carries them approaches the opening in the casing and are guided by end lugs k fixed to the baffle plates and coöperating with lugs k' fixed to the casing, the one over the reinforcing angle iron e of the casing and the other against the wall at f, thereby forming a complete closure to the interior of the casing on either side of the shutter (see Fig. 80 5 for details of the guiding lugs k and k').

Fig. 4 shows baffle plates attached to the shutter as in Fig. 3 but hinged instead of riveted; they are preferably of heavy stiff material, whereas the plates of Fig. 3 are 85 preferably relatively thin and resilient.

In the first embodiment of my invention as disclosed in Figs. 1 and 2, it is obvious that I may, if I prefer, substitute for the fusible link a catch k₂, as shown in detail 90 in Fig. 9. In such case it will be necessary to release the baffle plates by hand in case of fire or they may be so released each night, for example, at the close of the day's business.

In the various modifications shown I have provided baffle plates and, therefore, protection on each side of the shutter. In many cases, however, the risk of fire attaches only to one side of the shutter as, for example, 100 where an engine room is to be shut off from a warehouse or mill room in which there is neither inflammable material nor means capable of easily starting a fire. In such case, it may be preferred to omit the device from 105 that side of the shutter which is considered reasonably safe, and it is obvious that such omission does not lie outside of the limits of my invention nor dispense with the advantages which I have set forth.

Figs. 6 and 7 show two of the preceding modifications of my invention as applied to a straight sliding shutter; at the top the baffle plate is attached to the casing or wall and at the bottom to the shutter proper.

Instead of using gravity or guiding means to bring the baffle plates into position, other means may, obviously, be employed. Thus in Fig. 8 a spring S throws the baffle plate k³ into operative relation so soon as the fusible link L is opened by the heat.

The casing F of Figs. 1 and 2 may, for the purposes of my invention, be equivalent by the groove space F' in which the shutter may move, as in Fig. 7, or into which the 125 shutter may retire upon opening. For the purposes of my invention also, a door and a shutter may be considered as the same structures and I wish the terms so to be understood.

I do not desire to limit myself to the specific forms of a device as shown in the drawings, since it is clear that many other arrangements may be utilized without departing from the spirit of the invention, and I therefore claim:

1. In a fire resistant shutter adapted to move into a casing on opening, a fire resistant slat movably attached to supporting means independent of said casing and immediately adjacent to the entrance of said casing, said slat being adapted to substantially close the juncture of said shutter with said casing when said shutter is closed, substantially as and for the purpose described.
2. In a rolling metallic shutter adapted to move into a casing on opening, a fire resistant slat hingeably attached to supporting means independent of both shutter and casing and immediately adjacent to the entrance of said casing said slat being adapted to substantially close the juncture of said shutter with said casing when said shutter is closed, substantially as and for the purpose described.
3. In combination in a rolling metallic shutter, the shutter coil, a fire resistant casing inclosing said shutter coil and provided with an entrance through which the shutter is adapted to pass, supporting means to which said casing is fixed, and a fire resistant slat hingeably attached to said supporting means immediately adjacent to the entrance of said casing and adapted to substantially close the juncture of said shutter with said casing when said shutter is closed, substantially as and for the purpose described.

4. In combination in a rolling metallic shutter, the shutter coil, a fire resistant casing inclosing said shutter coil and provided with an entrance slot through which the shutter is adapted to pass when operated, supporting means to which the said casing is fixed, a fire resistant slat hingeably attached to said supporting means immediately adjacent to the entrance of said casing, a weight coöperating with said slat and adapted to hold said slat in closed relation to the shutter, and means fusible at a predetermined temperature adapted to retain said slat in normally open position, substantially as and for the purpose described.

5. In combination in a rolling metallic shutter, the shutter coil, a fire resistant casing inclosing said shutter coil and provided with an entrance slot through which the shutter is adapted to pass when operated, supporting means to which said casing is fixed, and a fire resistant slat on each side of the shutter hingeably attached to said supporting means immediately adjacent to the entrance of said casing, said slats being adapted to substantially close the juncture of said shutter with said casing on each of said shutter sides when said shutter is closed, substantially as and for the purpose described.

In testimony whereof I have hereunto set my hand.

JAS. G. WILSON.
